(57) **CLAIM**

The ornamental design for a cordless electric drill, as shown and described.

DESCRIPTION

FIG. 1 is a right side elevational view of a cordless electric drill;

FIG. 2 is a left side elevational view;

FIG. 3 is a top plan view;

FIG. 4 is a bottom plan view;

FIG. 5 is a front end elevational view; and,

FIG. 6 is a rear end elevational view.

The broken-line showings in all figures are for illustrative purposes only and form no part of the claimed design.
